CLAIM

The ornamental design for a tie stall divider, as shown and described.

DESCRIPTION

FIG. 1 is a left side elevational view of a tie stall divider showing our new design, the right side being a mirror image of the left side shown;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view thereof;

FIG. 7 is a left side elevational view of a second embodiment of FIG. 1, the right side being a mirror image of the left side shown;

FIG. 8 is a rear elevational view thereof, the front elevational view being identical to FIG. 2; and,

FIG. 9 is a bottom plan view thereof, the top plan view being identical to FIG. 4.

The broken-line representation of a cow stall in FIG. 1 is for illustrative purposes only, and forms no part of the claimed design.
